MEANS FOR SECURING PRINTING PLATES
TO THEIR CYLINDERSTheodore R. Ziebell, Milwaukee, Wis., assignor to
C. B. Cottrell & Sons Company, Westerly, R. I.,
a corporation of Delaware

Application May 7, 1952, Serial No. 286,560

32 Claims. (Cl. 101—378)

1

My invention is directed to novel means for securing printing plates to their cylinders, the object being to provide a plate hook with a novel jaw assembly which will exert a combined tension and compression on the printing plate to prevent endwise displacement of the plate under the severe strains thereon due to the high speed now required in rotary printing.

My invention comprises a plate hook of any well known or approved construction, provided with a novel jaw assembly which comprises an inner plate edge-contacting jaw member pivoted in the body of the plate hook so as to be swung laterally with respect thereto, and an assembly outer plate tensioning jaw member slidably interlocked with the inner jaw member and also slidably engaged with its adjacent edge of the printing plate.

A further object of my invention is to provide a plate hook of the above character in which the removable outer jaw member is slidably interlocked with the inner jaw member by a coacting undercut tongue and groove connection and with the adjacent edge of the printing plate by a coacting flange and groove connection.

Another object of my invention is to provide a plate hook having a jaw assembly particularly designed for engaging the straight leading and trailing edges of a curved printing plate with a combined tension and compression effect.

A further object is to provide means for yieldingly holding the outer jaw member properly positioned on its inner jaw member.

A still further object is to provide a reversible outer jaw member so that it may be used to slidably engage the adjacent leading or trailing edge of another printing plate.

A still further object is to provide an outer jaw member of sufficient length to permit it to be slidably interlocked with a plurality of aligned inner jaw members.

A practical embodiment of my invention is represented in the accompanying drawings in which:

Fig. 1 represents a detail plan view of a portion of a spirally grooved plate cylinder with a curved printing plate secured thereon;

Fig. 2 represents an enlarged detail section taken in the plane of the line 2—2 of Fig. 1;

Fig. 3 represents an enlarged detail section taken in the plane of the line 3—3 of Fig. 1;

Fig. 4 represents a detail section taken in the plane of the line 4—4 of Fig. 3;

Fig. 5 represents a top plan view of the plate hook with the outer jaw member removed;

Fig. 6 represents an end view of the same;

2

Fig. 7 represents a side view of the same;

Fig. 8 represents a top plan view of the outer jaw member;

Fig. 9 represents a section taken in the plane of the line 9—9 of Fig. 8;

Fig. 10 represents a bottom plan view of the outer jaw member;

Fig. 11 represents a modified form of outer jaw member; and

Fig. 12 represents a side view of a suitable key for turning one of the double-winged locks and also for operating the movable member of the plate hook.

The plate cylinder 1 is shown as provided with spaced hook-receiving grooves 2 and their lock-engaging opposite side grooves 3. The usual racks 4 are shown along the bottoms of the spiral grooves 2.

The curved printing plate 5 is shown as having its curved opposite side edges 6 as beveled for clamping engagement by the jaws 7 of plate hooks 8 of any well known or approved construction.

The straight leading and trailing edges 9 of the printing plate 5 have grooves 10 milled or otherwise formed in their outer horizontal faces leaving upper and lower vertical edge surfaces 9a and 9b.

My improved jaw assembly for holding the leading and trailing edges of the printing plates under a combined tension and compression securely to its cylinder may be incorporated in plate hooks of various well known or approved types. I have chosen to show and describe the

30 jaw assembly as incorporated in a plate hook of the type shown, described and claimed in my co-pending application filed November 2, 1951, Serial No. 254,563. This plate hook includes a stationary member 11 provided with a short

35 toothed rack 12 adapted to be engaged with the cylinder groove rack 4 when the plate hook is properly positioned within its selected cylinder groove 2. The jaw bearing movable member 13 of the plate hook is shown as manually slidably on the inner hook member into and out of its

30 plate securing position by providing a key-operated screw 14 which is threaded through the stationary member 11 and rotatably mounted in the outer member 13. This plate hook is shown as provided with two double-winged spring-pressed locks 15 and 16 pivoted to swing laterally; the lock 15 being swung by the shank 17a of a

55 suitable key 17 into and out of sliding engagement with the side grooves 3 of the spiral cylinder groove 2.

My improved jaw assembly is shown as a combined plate tension and compression jaw including inner and outer elongated members 18 and 19. The inner jaw member 18 is pivoted in the plate hook, in the present instance, by being formed integral with the double-winged lock 16. This inner jaw member serves as a means for swinging the double-winged lock 16 into and out of its sliding engagement with the said side grooves 3.

The outer member 19 of the plate engaging jaw is provided with a depending flange 20 along one of its edges, which flange slidably fits within its groove 16 which extends along the straight leading or trailing edge 9 of the printing plate.

This outer jaw member 19 is removable and it is slidably interlocked with the inner or compression jaw member 18 as, for instance, by an undercut tongue and groove connection. In the present instance the inner jaw member 18 is provided with an open-ended undercut groove 21 for slidably receiving the undercut tongue 22 along the inner face of the outer jaw member 19. This undercut tongue 22 is preferably considerably shorter than the outer jaw member 19 to permit the engagement and disengagement of the two jaw members by an endwise movement considerably shorter than the length of the inner jaw member to allow the plate hooks to be spaced close to one another along their adjacent plate edge.

The outer face of the outer jaw member is shown as tapered from its flanged edge to its other edge to prevent interference with the printing operation.

The key-operated means for turning the screw 14 of the divided plate hook to advance and retract the outer member 19 of the plate hook includes a bevel gear 23 at the head of the screw, which bevel gear meshes with a bevel gear 24 rotatably mounted in the double-winged lock 16.

The bevel gear 24 is shown as provided with an angular bore 25 for receiving the shank 17b of the key 17, which shank may be readily inserted through the co-axial larger bore 26 through the inner jaw member 18, and the co-axial larger bore 27 through the outer jaw member after the jaw member has been slid into its proper position on the inner jaw member.

The means which I have shown for yieldingly holding the outer jaw member 19 in its proper position on the inner jaw member 18 comprises a shallow hole 28 in the outer face of the inner jaw member and a coacting spring-pressed ball 29 seated in the tongue 22 of the said outer member 19.

This outer member 19 may be reversed if so desired and then slid onto the inner member to allow the flange 20 of the outer member to slidably engage the groove 9 in the adjacent edge of another printing plate. To yieldingly hold the outer jaw member in its proper reversed position on the inner jaw member, the outer face of the inner jaw member is provided with a second shallow hole 30 in the outer face of the inner jaw member on the opposite side of the key-receiving hole 26 from the shallow hole 28.

In Fig. 11 I have shown the outer jaw member 19 as elongated sufficiently to coact with a plurality of inner jaw members 18. In the present instance I have shown three undercut tongues spaced apart sufficiently to permit the interlocking of the outer jaw member with the inner jaw members by a short sliding movement of the outer jaw member.

In operation, the plate hooks 8 are positioned on the cylinder with their undercut jaws 7 along the curved beveled edges 6 of the printing plate 5, and the plate hooks with the fixed and movable members 11 and 13 with their outer jaw members 19 removed are positioned along the leading and trailing straight edges 9 of the printing plate 5. The jaws 7 of the hooks 8 are then moved sufficiently to cause the jaws 7 to clamp the curved beveled side edges of the plate firmly to the cylinder. The movable members of the hooks 12, 13, 14 are adjusted to bring the inner jaws 18 into contact with the lower faces 9b of the leading and trailing edges of the plate. The undercut tongues of the outer jaw members 19 are then slid into the undercut grooves 21 of the inner jaw members 18, and the depending flanges 20 are slid at the same time into their plate edge grooves 16, to slidably lock the outer jaw members 19 to their inner jaw members 18 and to also slidably lock the outer jaw members 19 to the leading and trailing edges of the printing plate.

The outer jaw members 19 are yieldingly held in position on the inner jaw members 18 to align the bores 26 and 27 through the inner and outer jaw members with the angular bore 25 in the bevel gear 24, to permit the insertion of the shank 17b of the key 17 to cause the outer jaw members 19 to exert the proper tension on the leading and trailing edges of the printing plate.

In actual printing operations, the printing plate is subjected to a certain amount of travel or thrust pressure and this will be taken care of by the contact of the inner and outer jaw members 18 and 19 with the upper and lower vertical edge portions 9a and 9b of the printing plate. This causes a combined tension and compression effect on the printing plate to hold it rigidly and securely to the cylinder during printing operations.

It is evident that various changes may be resorted to in the construction, form and arrangements of the several parts without departing from the spirit and scope of this invention and hence it is not intended to be limited to the particular embodiment shown and described herein.

What I claim is:

1. A spirally grooved cylinder, a curved printing plate and means for securing it to the cylinder, including combined plate tension and compression plate hooks comprising pivoted plate engaging inner jaw members and removable plate engaging outer jaw members slidably interlocked with the inner jaw members and locked to the leading and trailing edges of the printing plate.

2. A spirally grooved cylinder, a curved printing plate and means for securing it to the cylinder, including combined plate tension and compression plate hooks comprising pivoted plate engaging inner jaw members and removable and reversible plate engaging outer jaw members slidably interlocked with the inner jaw members and locked to the leading and trailing edges of the printing plate.

3. A spirally grooved cylinder, a curved printing plate and means for securing it to the cylinder, including combined plate tension and compression plate hooks comprising pivoted locks, plate engaging inner jaw members formed integral therewith, and removable plate engaging outer jaw members slidably interlocked with the inner jaw members and locked to the leading and trailing edges of the printing plate.

4. A spirally grooved cylinder, a curved print-

ing plate and means for securing it to the cylinder, including combined plate tension and compression plate hooks comprising pivoted locks, plate engaging inner jaw members formed integral therewith, and removable and reversible plate engaging outer jaw members slidably interlocked with the inner jaw members and locked to the leading and trailing edges of the printing plate.

5. A spirally grooved cylinder, a curved printing plate having grooved straight edges, provided with upper and lower jaw contact faces, and means for securing the plate to the cylinder, including combined plate tension and compression plate hooks comprising pivoted plate engaging inner jaw members and removable plate engaging flanged outer jaw members slidably interlocked with the inner jaw members and locked to said grooved straight edges, said outer and inner jaw members having faces arranged to be brought into contact with the said upper and lower jaw contact faces and means for holding the outer jaw member in position on the inner jaw member during the plate securing operation.

6. A spirally grooved cylinder, a curved printing plate having grooved straight edges, provided with upper and lower jaw contact faces, and means for securing the plate to the cylinder, including combined plate tension and compression plate hooks comprising pivoted plate engaging inner jaw members and removable and reversible plate engaging flanged outer jaw members slidably interlocked with the inner jaw members and locked to said grooved straight edges, said outer and inner jaw members having faces arranged to be brought into contact with the said upper and lower jaw contact faces and means for holding the outer jaw member in position on the inner jaw member during the plate securing operation.

7. A spirally grooved cylinder, a curved printing plate and means for securing the leading and trailing edges of the printing plate to the cylinder, including combined plate tension and compression plate hooks comprising pivoted plate engaging inner jaw members and removable plate engaging outer jaw members slidably interlocked with the inner jaw members and locked to the said leading and trailing edges of the printing plate, and means for yieldingly holding the outer jaw members in position on their inner jaw members.

8. A spirally grooved cylinder, a curved printing plate and means for securing the leading and trailing edges of the printing plate to the cylinder, including combined plate tension and compression plate hooks comprising pivoted plate engaging inner jaw members and removable and reversible plate engaging outer jaw members slidably interlocked with the inner jaw members and locked to the said leading and trailing edges of the printing plate, and means for yieldingly holding the outer jaw members in position on their inner jaw members.

9. A spirally grooved cylinder, a curved printing plate and means for securing the leading and trailing edges of the printing plate to the cylinder, comprising combined plate tension and compression plate hooks, pivoted locks, plate engaging inner jaw members formed integral therewith, and removable plate engaging outer jaw members slidably interlocked with the inner jaw members and locked to the said leading and trailing edges of the printing plate, and means

for yieldingly holding the outer jaw members in position on their inner jaw members.

10. A spirally grooved cylinder, a curved printing plate and means for securing the leading and trailing edges of the printing plate to the cylinder, comprising combined plate tension and compression plate hooks, pivoted locks, plate engaging inner jaw members formed integral therewith, and removable and reversible plate engaging outer jaw members slidably interlocked with the inner jaw members and locked to the said leading and trailing edges of the printing plate, and means for yieldingly holding the outer jaw members in position on their inner jaw members.

11. A spirally grooved cylinder, a curved printing plate and means for securing the leading and trailing edges of the plate to the cylinder, including combined plate tension and compression plate hooks comprising, pivoted plate engaging inner jaw members, removable plate engaging outer jaw members, and undercut tongue and groove connections between the outer and inner jaw members coacting to slidably interlock the outer jaw members with the inner jaw members, and flange and groove connections between the outer jaw members and the printing plate coacting to slidably lock the outer jaw members to the said leading and trailing edges of the printing plate.

12. A spirally grooved cylinder, a curved printing plate and means for securing the leading and trailing edges of the plate to the cylinder, including combined plate tension and compression plate hooks comprising, pivoted plate engaging inner jaw members, removable and reversible plate engaging outer jaw members, and undercut tongue and groove connections between the outer and inner jaw members coacting to slidably interlock the outer jaw members with the inner jaw members, and flange and groove connections between the outer jaw members and the printing plate coacting to slidably lock the outer jaw members to the said leading and trailing edges of the printing plate.

13. A spirally grooved cylinder, a curved printing plate and means for securing the leading and trailing edges of the plate to the cylinder, including combined plate tension and compression plate hooks, locks pivoted in the plate hooks, plate engaging inner jaw members formed integral with said locks, and removable plate engaging outer jaw members, undercut tongue and groove connections between the outer and inner jaw members coacting to slidably interlock the outer jaw members with their inner jaw members, and flange and groove connections between the outer jaw members and the printing plate coacting to slidably lock the outer jaw members to the said leading and trailing edges of the printing plate.

14. A spirally grooved cylinder, a curved printing plate and means for securing the leading and trailing edges of the plate to the cylinder, combined plate tension and compression plate hooks, including locks pivoted in the plate hooks, plate engaging inner jaw members formed integral with said locks, and removable and reversible plate engaging outer jaw members, undercut tongue and groove connections between the outer and inner jaw members coacting to slidably interlock the outer jaw members with their inner jaw members, and flange and groove connections between the outer jaw members and the printing plate coacting to slidably lock the

outer jaw members to the said leading and trailing edges of the printing plate.

15. A spirally grooved cylinder, a curved printing plate and plate hooks for securing the leading and trailing edges of the plate to the cylinder, including pivoted inner jaw members, removable outer jaw members and undercut tongue and groove connections coacting to slidably lock the outer jaw members to the inner jaw members, flange and groove connections coacting to slidably lock the outer jaw members to the said leading and trailing edges of the printing plate, and means for yieldingly holding the outer jaw members in position on their inner jaw members.

16. A spirally grooved cylinder, a curved printing plate and plate hooks for securing the leading and trailing edges of the plate to the cylinder, including pivoted inner jaw members, removable and reversible outer jaw members, and undercut tongue and groove connections coacting to slidably lock the outer jaw members to the inner jaw members, flange and groove connections coacting to slidably lock the outer jaw members to the said leading and trailing edges of the printing plate, and means for yieldingly holding the outer jaw members in position on their inner jaw members.

17. A spirally grooved cylinder, a curved printing plate and plate hooks for securing the leading and trailing edges of the plate to the cylinder, including locks pivoted in the plate hooks, inner jaw members formed integral with said locks, and removable outer jaw members, undercut tongue and groove connections coacting to slidably lock the outer jaw members to their inner jaw members, flange and groove connections coacting to slidably lock the outer jaw members to the said leading and trailing edges of the printing plate, and means for yieldingly holding the outer jaw members in position on their inner jaw members.

18. A spirally grooved cylinder, a curved printing plate and plate hooks for securing the leading and trailing edges of the plate to the cylinder, including locks pivoted in the plate hooks, inner jaw members formed integral with said locks, and removable and reversible outer jaw members, undercut tongue and groove connections coacting to slidably lock the outer jaw members to their inner jaw members, flange and groove connections coacting to slidably lock the outer jaw members to the said leading and trailing edges of the printing plate, and means for yieldingly holding the outer jaw members in position on their inner jaw members.

19. A spirally grooved cylinder, a curved printing plate, and means for securing it to the cylinder, including combined plate tension and compression plate hooks comprising, a lined plate engaging inner jaw members and a removable plate engaging outer jaw member slidably interlocked with a plurality of the inner jaw members and locked to the adjacent edge of the printing plate.

20. A spirally grooved cylinder, a curved printing plate, and means for securing it to the cylinder, including combined plate tension and compression plate hooks comprising, a lined plate engaging inner jaw members and a removable and reversible plate engaging outer jaw member slidably interlocked with a plurality of the inner jaw members and locked to the adjacent edge of the printing plate.

21. A spirally grooved cylinder, a curved printing plate having grooved leading and trailing

edges, and means for securing the plate to its cylinder including plate hooks comprising, pivoted plate engaging inner jaw members and removable plate engaging outer jaw members, the inner jaw members having short undercut grooves extending from end to end thereof, and the outer jaw members having short undercut grooves fitting within said undercut grooves for slidably interlocking the outer jaw members with the inner jaw members, and flanges on the outer jaw members fitting the plate edge grooves for slidably locking the outer members to the plate.

15 20 25 30 35 40 45 50 55 60 65 70 75 80 85 90 95

22. A spirally grooved cylinder, a curved printing plate having grooved leading and trailing edges, and means for securing the plate to its cylinder including plate hooks comprising, pivoted plate engaging inner jaw members and removable and reversible plate engaging outer jaw members, the inner jaw members having short undercut grooves extending from end to end thereof, and the outer jaw members having short undercut grooves fitting within said undercut grooves for slidably interlocking the outer jaw members with the inner jaw members, and flanges on the outer jaw members fitting the plate edge grooves for slidably locking the outer members to the plate.

23. A combined plate tension and compression printing plate hook comprising, a pivoted plate engaging inner jaw member, and a removable plate engaging outer jaw member slidably interlocked with the inner jaw member and adapted to slidably engage the printing plate.

24. A combined plate tension and compression printing plate hook comprising, a pivoted plate engaging inner jaw member, and a removable and reversible plate engaging outer jaw member slidably interlocked with the inner jaw member and adapted to slidably engage the printing plate.

25. A combined plate tension and compression printing plate hook comprising, a pivoted plate engaging inner jaw member, a removable plate engaging outer jaw member slidably interlocked with the inner jaw member and adapted to slidably engage the printing plate, and means for yieldingly holding the outer jaw member in position on the inner jaw member.

50 55 60 65 70 75 80 85 90 95

26. A combined plate tension and compression printing plate hook comprising, a pivoted plate engaging inner jaw member, a removable and reversible plate engaging outer jaw member slidably interlocked with the inner jaw member and adapted to slidably engage the printing plate, and means for yieldingly holding the outer jaw member in position on the inner jaw member.

27. A combined plate tension and compression printing plate hook comprising, a pivoted lock, a plate engaging inner jaw member formed integral therewith, and a removable plate engaging outer jaw member slidably interlocked with the inner jaw member and adapted to slidably engage the printing plate.

28. A combined plate tension and compression printing plate hook comprising, a pivoted lock, a plate engaging inner jaw member formed integral therewith, and a removable and reversible plate engaging outer jaw member slidably interlocked with the inner jaw member and adapted to slidably engage the printing plate.

29. A combined plate tension and compression printing plate hook comprising, a pivoted lock, a plate engaging inner jaw member formed integral therewith, and a removable plate engaging outer jaw member slidably interlocked with the

inner jaw member and adapted to slidably engage the printing plate, and means for yieldingly holding the outer jaw member in position on the inner jaw member.

30. A combined plate tension and compression printing plate hook comprising, a pivoted lock, a plate engaging inner jaw member formed integral therewith, and a removable and reversible plate engaging outer jaw member slidably interlocked with the inner jaw member and adapted to slidably engage the printing plate, and means for yieldingly holding the outer jaw member in position on the inner jaw member.

31. A combined plate tension and compression printing plate hook comprising, a pivoted plate engaging inner jaw member, a removable plate engaging outer jaw member, and an undercut tongue and groove connection coacting to slidably interlock the upper jaw member with the lower jaw member, said upper jaw member having a depending flange adapted to enter a groove in the edge of the printing plate for slidably locking the upper jaw member thereto.

5 32. A combined plate tension and compression printing plate hook comprising, a pivoted plate engaging inner jaw member, a removable and reversible plate engaging outer jaw member, and an undercut tongue and groove connection coacting to slidably interlock the upper jaw member with the lower jaw member, said upper jaw member having a depending flange adapted to enter a groove in the edge of the printing plate 10 for slidably locking the upper jaw member thereto.
